US0D1072666S

(12) United States Design Patent (10) Patent No.: US D1,072,666 S
(45) Date of Patent: * Apr. 29, 2025

(54) PLANT STAND

(71) Applicant: Wanlan Xie, Anji County (CN)

(72) Inventor: Wanlan Xie, Anji County (CN)

() Term: 15 Years

(21) Appl. No.: 35/520,060

(22) Filed: Jan. 26, 2024

(80) Hague Agreement Data

Int. Filing Date: Jan. 26, 2024

Int. Reg. No.: DM/235015

Int. Reg. Date: Jan. 26, 2024

Int. Reg. Pub. Date: Feb. 16, 2024

(51) LOC (15) Cl. 11-02

(52) U.S. Cl.

USPC D11/156; D11/143; D11/155; D8/1;
D6/403
